UNITED STATES PATENT OFFICE.

LANGDON McCORMICK, OF NEW YORK, N. Y.

ILLUSIONARY APPARATUS FOR THEATERS.

1,372,969.

Specification of Letters Patent. Patented Mar. 29, 1921.

Application filed April 27, 1920. Serial No. 377,072.

To all whom it may concern:

Be it known that I, LANGDON McCORMICK, a citizen of the United States, residing at Navarre Hotel, New York, in the county of New York and State of New York, have invented certain new and useful Improvements in Illusionary Apparatus for Theaters, of which the following is a specification.

10 This invention relates to improvements in a method of producing illusionary effects on a screen and used in connection with theatrical appliances.

15 The prime object of the invention is to utilize a plurality of opaque objects or sections of scenery, and a plurality of lights, and so manipulate same as to produce on a translucent curtain or screen, a silhouette or shadow of the objects or of the scenery 20 sections, to form a base picture and diffuse, blend or dissolve the lights to vary the scenic effect.

It has been found from practical experience that the shadows from scenic sections 25 produced on a screen, may be changed materially to bring about entirely different pictures by simply altering the angularity of the lights, or by diffusing the lights or interposing other lights between the sections to diffuse rays of light to make more pronounced certain features, and other features of less importance.

It has also been found that by forming a silhouette or base picture on a screen and 35 employing lights of different colors, or representation of scenes from a stereopticon or moving picture machine, varied and unusual results are obtained, and varied scenic effects may be constantly produced.

40 In other words, the method herein described is capable of producing on a screen or curtain a constantly changing scene from the same source, the illusionary effect being largely brought about by the manipulation 45 of the various lights and shadows.

In the accompanying drawing, representing diagrammatically one way of illustrating the method:

Figure 1 is a front view of a stage illustrating the invention.

Fig. 2 is a plan view of the same.

Fig. 3 is a side view.

Fig. 4 is a detail view of one of the scenic sections.

55 Fig. 5 is a diagrammatic view illustrating

ing a complete system for carrying out my invention.

1 indicates a stage, and substantially covering the opening about said stage is a translucent screen or curtain 2. In rear of the curtain are what I shall term opaque objects or scene sections 3—4—5—6 and 7, each mounted on a truck 8. The sections 3 and 4, are shown somewhat smaller than the sections 5 and 6, while the section 7 is single and disposed in rear of and mid-way between the side sections. The sections 3—4 and 5—6 as shown, are in pairs, while section 7 is in a single piece. The pairs of sections and the single section are spaced apart sufficient distance to throw the desired shadows, and to permit of the placing of the proper lights to accomplish the desired result.

Attached to opposite ends of each truck 75 of the pairs are the opposite ends of cables 9, which pass around sheaves 10, and are so wound as to pull on one end and slack the opposite end of each cable when power is applied to one of the sheaves. The power 80 sheave of each truck is connected to a reversible motor 10. With the arrangement, when a motor is operated a truck may be moved laterally to change the relation of the scenic section with other scenic sections to 85 produce the desired shadow on the screen.

Certain ones or all the sections may if desired be hinged to a frame, the free ends being thereby movable toward or from the screen to change the contour of the shadows 90 of the scenic section or sections. The means to accomplish this action may consist of a sheave 11, driven by a reversible motor 12, and an endless cable 13, having its opposite ends attached to the sides of a truck and 95 wound several times around the power sheave 11, and a guide sheave 14.

Located behind and near the bottom of each scenic section will be one or a series of lamps 15, each having a shade 16 operated 100 by a motor 17. These lamps are so disposed as to throw rays of light up toward the top edge of the scene directly in front, and to diffuse the light between the adjacent scene sections, and each lamp will be individually controlled to produce a predetermined production on the screen.

In rear of the single scene section will be a lamp 20, mounted to slide, as by a sleeve 21, on a standard 22, but rotatable there-

- with. The standard and sleeve are rotated by a motor 23, and the sleeve, hence the lamp is raised or lowered by a motor and gearing indicated at 24.
- 5 This lamp is disposed behind all the scene sections, and below the top edges of the latter so that the rays of light will insure of shadows being thrown on the translucent screen.
- 10 In addition to the lamp 20, other lamps may be disposed behind the scene sections, to direct rays of light at various angles to change the picture depicted on the screen at will. I have shown two lamps indicated at 15 30 and 31, in addition to the central lamp 20, but of course other lamps may be added if desired.
- 20 Coöoperating with the shadow on the screen I employ a stereopticon or moving picture machine 34, located in front of the screen and at such position that the rays of light, or the moving picture as the case may be, will be directed on the front surface. This machine will be provided with the 25 usual means for diffusing the light, introducing various colored rays, and such other essentials as to control the location, color, tone, etc., of the light or picture thrown on the screen to blend with or form part of 30 the predetermined picture.
- 35 In order to control the various shadows and the lights necessary to produce the picture effect, it is quite essential that the various switches be so arranged as to be conveniently operated. However in the drawing the circuits and switches are shown somewhat scattered and are purely of dia- 40 grammatic form, and each will now be described.
- 45 From the motor 23 leads a wire 50, terminating in a contact 51. Also leading from the motor is a battery wire 52, including a battery 53, and having a switch 54, the latter adapted to coöperate with the contact 51. When the switch 54 is closed the motor 23 will slowly rotate the lamp in one direction to radially change the rays of light from the central lamp 20. To reverse the motor a switch and circuit 56, may be provided.
- 50 From the motor 24, leads a wire 57, having a terminal contact 58, and a second wire 59 connects with the battery wire 52, and from the latter extends a branch 60, having a switch 61, to coöperate with the contact 58. When the switch is closed the motor through the gearing will elevate the lamp 20, the connection 62, permitting of the lamps being rotated and moved vertically. To reverse the motor to lower the lamp, a circuit and switch 63, may be provided, whereby to lower the lamp to adjust it in the desired position.
- 55 The side lamp 30 is provided with a motor
- 60 to rotate it, the motor being controlled by a circuit 64, battery 65, and switch 66. The rotary movement of the lamp may be reversed by means of a circuit, battery and switch 67. This lamp may also be raised by a motor 67^a, controlled by a circuit 68, battery 65, and switch 70. The motor may be reversed by a circuit 71. The side lamp 31, may be rotated by a motor 72, controlled by a circuit 73, and switch 74, and may be reversed by a circuit and switch 75. Lamp 31, may be raised by a circuit 76, controlled by a switch 77. The reverse movement may be under the control of a circuit and switch 78.
- 65 The shade of the lamp 15 in rear of the central scenic section 7, is rotated and controlled in one direction by a motor, circuit 81, battery 53, and switch 82, and the motion of the shade may be reversed by a circuit 83 and switch 84. The lamp 15 is supplied with current by a circuit 85, including a resistance box 86 to increase or decrease the light at will.
- 70 The shades of the lamps 15 behind the scenic sections 5 and 6, are controlled by circuits and switches 87, and reversing circuits and switches 88. The drums 11 of the sections adjacent these lamps are controlled by circuits and switches 89, while the trucks carrying the lamps are controlled by circuits and switches 90, and reverse circuits and switches 91. The lamps are supplied with current through circuits 91^a, including a resistance 91^b.
- 75 The shades of the lamps 15, in rear of the scenic sections 3 and 4 are controlled in one direction by circuits and switches 92, and reverse currents and switches 93 are provided to move the shades in the opposite direction. The lamps behind the sections 3 and 4 are supplied with current by circuits 95 having resistance 96 and the trucks carrying these lamps are controlled by circuits 96^a, and switches 97. The reverse movement of the trucks may be controlled by reverse circuits and switches 98.
- 80 The stereopticon or moving picture apparatus is controlled by a circuit 99, resistance 100, and switch 101, and such other circuits necessary to bring into action at predetermined times the various elements of the machine and produce the desired results.
- 85 Lights in rear are all diffused and are of various colors according to the scene depicted and are moved from time to time to produce the desired shadow.
- 90 Lights are thrown on the front of the screen to match up or synchronize with the shadows produced by the lights and scenic mechanism at the rear. The lights in front are made stronger at times than the shadows to obtain the desired effects, or pictures

are thrown in to coöperate with the shadow effect, or the front lights are dimmed to produce the stronger effect of the shadows.

5 Lights in front and back will be controlled by switches at a switch board so that the harmonizing of the two sets of lights may be controlled to obtain the desired effect.

10 The trucks will be made to be controlled by motive power and under the control of the operator at the switch board.

15 The trucks will be hinged and otherwise bendable to obtain various angles to effect the desired shadows to match up with the lights at the front.

20 The scenic sections are provided with openings or translucent portions that the outline of the shadow picture on the screen may have light spots to be worked in with various colored lights from the front or rear to form some part of the predetermined sketch.

What I claim is:—

25 1. The method of producing illusionary effects on a translucent screen consisting in arranging a plurality of objects depicting various portions of a determinate scene in rear of the screen, and directing rays of light in rear of the objects to produce on the screen the shadows of the objects and directing rays of light on the front of the screen to blend and harmonize with the shadows to complete the predetermined scene.

30 2. The method of producing illusionary effects on a translucent screen consisting in arranging a plurality of objects depicting various portions of a determinate scene in rear of the screen, and moving rays of lights in rear of the objects to produce on the screen various shadows of the objects and change their outline to produce a predetermined picture on the front of the screen.

35 3. The method of producing illusionary effects on a translucent screen consisting in producing at the rear of the screen shadows, which appear on the front surface of the screen, and simultaneously diffusing rays of light and throwing pictures on the front of the screen to blend with and form with the shadows a predetermined picture.

40 4. The method of producing illusionary effects on a translucent screen consisting in locating a plurality of spaced objects in rear of the screen, throwing the rays of light the source of which is in rear of the objects to produce predeterminate shadows on the front of the screen, and changing the picture by diffusing rays of light between the objects.

45 5. The method of producing illusionary effects on a translucent screen consisting in locating a plurality of spaced objects in rear of the screen, throwing the rays of light the source of which is in rear of the objects to

produce predeterminate shadows on the front of the screen, and changing the picture by diffusing rays of light between the objects, and diffusing rays of light and throwing pictures on the front of the screen.

50 6. The method of producing illusionary effects on a translucent screen consisting in throwing rays of light behind a series of objects in rear of the screen to produce a shadow picture on the front of the screen, then moving the source of light with reference to the objects to constantly change the outline of the shadow picture.

55 7. The method of producing illusionary effects on a screen consisting in throwing rays of light from a series of sources behind a series of objects in rear of the screen to produce a shadow picture on the front of the screen, then creating relative movement between the objects and the series of sources of light to produce a constant changing of the outline of the picture, and simultaneously diffusing rays of light on the front of the screen to assist in producing with the shadows a predetermined picture.

60 8. The method of producing illusionary effects on a translucent screen consisting in placing a series of objects in rear of the screen and a plurality of sources of light in rear of the objects to produce on the front of the screen a shadow picture, and simultaneously diffusing various colored rays of lights between the series of sources of light and the rear surface of the screen to produce on the front of the latter predetermined colored shadow pictures.

65 9. The method of producing illusionary effects on a translucent screen consisting in placing a series of objects in rear of the screen and a plurality of sources of light in rear of the objects to produce on the front of the screen a shadow picture, and simultaneously diffusing various colored rays of lights between the series of sources of light and the rear surface of the screen to produce on the front of the latter predetermined colored shadow pictures, and simultaneously directing and diffusing rays of colored lights on the front of the screen to blend with and harmonize with the shadow picture to change its form and effect.

70 10. The method of producing illusionary effects on a translucent screen consisting in throwing a base shadow picture on the screen from the rear and exposed on the front surface, and simultaneously directing and diffusing various colored lights on the front of the screen to change the form and outline of the shadow picture.

75 11. The method of producing illusionary effects on a translucent screen consisting in throwing a base shadow picture on the screen from the rear and exposed on the front surface, and simultaneously directing and dif-

fusing various colored lights and pictures on the front of the screen to change the form and outline of the shadow picture.

12. The method of producing illusionary effects on a translucent screen consisting in directing and diffusing various colored lights and pictures on the front of the screen and simultaneously moving a series of objects in rear of the screen in front of rays of light to produce shadows to complete the picture on the front surface of the screen.

13. The method of producing illusionary effects on a translucent screen consisting in producing constantly changing shadows on the screen and constantly changing degrees of light to form a base shadow picture, and simultaneously on the front of the screen and in coöperative relation with the base picture

colored lights and sub-pictures to form a predetermined scene.

20

14. The method of producing illusionary effects consisting in producing a shadow on a screen to form a base picture and directing, dissolving and blending colored lights adding to the base picture and constantly changing the view.

25

15. The method of producing illusionary effects on a translucent screen consisting in throwing a shadow base picture on the screen and directing, dissolving and blending colored lights on opposite sides of the screen to add to and constantly change the base shadow picture.

30

In testimony whereof I affix my signature.

LANGDON McCORMICK.
